CLAIM

The ornamental design for a S-band universal terminal, as shown and described.

DESCRIPTION

FIG. 1 is a top perspective view of an S-band universal terminal in accordance with our new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines in the drawings depict portions of the S-band universal terminal that form no part of the claimed design.

1 Claim, 7 Drawing Sheets
